HIS ATTORNEY

UNITED STATES PATENT OFFICE.

LESLIE R. N. CARVALHO, OF TOLEDO, OHIO, ASSIGNOR TO THE CLOSURE SERVICE COMPANY, OF TOLEDO, OHIO, A CORPORATION OF OHIO.

RECEPTACLE CLOSURE.

Application filed July 5, 1923. Serial No. 649,576.

My invention relates to receptacles and closures therefor. An object of the invention is to provide an improved form of closure or cap, simple in construction, inexpensive to manufacture, which may be repeatedly applied to the container, and which is free from various defects found in closure devices at present in use.

It is also an object to provide highly effective yet simple retaining means for a closure or cap, said means including circumferentially spaced lugs stamped inwardly from the metal making up the cap and so located that they present a maximum degree of resistance to yielding under pressure.

Other objects of the invention will appear hereinafter.

In the accompanying drawings:

20 Figure 1 is a part sectional elevation of a receptacle and closure constructed in accordance with the present invention, part of the receptacle being broken away.

25 Figure 2 is a top plan view of the closure or cap.

Figure 3 is a perspective view of the cap on a larger scale, parts being broken away.

Figure 4 is a part sectional plan of a portion of the cap.

30 The closure or cap comprises a cover portion 6 and a skirt or flange portion 7. The flange portion is formed with a circumferential rib 8 or apron which is preferably located a short distance above the lower edge 9 of the flange and has an oblique top portion. The lower portion of the skirt 7, beneath oblique top of the rib 8, is bent inwardly and then outwardly to provide a flat annular surface 10 at the bottom of the

40 cap. In other words, the lower portion is folded upon itself, the margin of the lower fold terminating at a point inwardly from the rib periphery to prevent contact with a user's fingers. At intervals along the rib

45 8, the metal is bent inwardly to provide inwardly projecting lugs or rib sections 11. It will be noted that the sheet metal forming the cap is slit along the edges 12 above the lower fold to permit the metal forming

50 said lugs to be bent inward. The cap is applied to a receptacle 13 formed with inclined or spiral threads 14 on the neck portion thereof, said threads corresponding in position and number to the holding lugs 11 on the cap. A gasket 15 within the cap pro-

vides a tight seal when the cap is placed in position on the container. By forming the rib 8 and the holding ribs 11 from a portion of the material above the lower edge of the skirt 7 and separated from said edge, 60 the strength of said ribs is increased as compared with the usual constructions in which the lower margin of the skirt is shaped to form means for holding the cap on the container. Moreover, with the present construction, the lower side of the cap presents a smooth unbroken surface 10.

Modifications may be resorted to within the spirit and scope of my invention.

What I claim is:

1. A sheet metal cap comprising a cover portion and a flange portion projecting downwardly therefrom, said flange portion being bent outwardly to form an annular rib, the bottom portion of the flange being bent outwardly horizontally beneath said rib closely adjacent thereto and parallel therewith to provide a smooth substantially flat annular double fold surface at the bottom of said flange. 70

2. A sheet metal cap comprising a cover portion and a flange portion projecting downwardly therefrom, said flange portion being bent outwardly to form an annular rib, the lower side of which is horizontally 75 disposed, the bottom portion of the flange being bent outwardly horizontally beneath said rib to provide a smooth substantially flat annular two-ply surface at the bottom of said flange, said rib having portions 80 thereof bent inward to form holding lugs at intervals along said rib, said bent inward portions so shaped as to maintain the rib in substantial continuity.

3. A closure for a receptacle comprising 95 a cover portion and a depending skirt or flange portion, said flange portion being shaped to provide a circumferential rib, a strengthening horizontally disposed fold under said rib, and forming a substantial integral part of said rib, said rib being slitted at intervals, and sections of the rib between adjacent slits being bent inwardly to form holding ribs for attachment to a receptacle. 100

4. A closure for a receptacle comprising a cover portion and a depending skirt or flange portion, said flange portion being shaped to provide a circumferential rib, the lower side of which is reenforced by a fold 105 of the margin of said flange upon itself, said 110

- rib being slitted at intervals, and sections of the rib between adjacent slits being bent inwardly to form holding ribs for attachment to a receptacle, said skirt comprising
- 5 an annular flange portion beneath the rib close to and parallel with the rib, said flange portion being bent outwardly to provide a horizontally disposed annular reenforcing strip forming the bottom surface of the cap.
- 10 5. The combination of a receptacle having a neck portion provided with external spiral threads spaced at intervals around the neck, and a cap forming a closure for said receptacle, said cap comprising a cover portion
- 15 and a flange portion, the latter provided with an annular rib intermediate the top and bottom of the flange portion, said rib comprising portions projecting outwardly from the body of the flange and alternating with
- 20 indent holding portions, said holding portions positioned to cooperate with said threads for holding the cap on the receptacle, the portion of the flange beneath said rib being bent outwardly at the lower edge of
- 25 the rib to form a smooth unbroken bottom surface for the cap.
6. A closure for a receptacle comprising a cover portion and a depending flange portion, said flange portion being shaped adjacent its lower extremity to provide a circumferential apron horizontally disposed, said apron consisting of an oblique top portion, and a double walled horizontal flat lower portion, said apron being slitted at
- 35 intervals to provide segregated portions, said portions being bent inwardly to form holding lugs for attachment to a receptacle.
7. A closure for a receptacle comprising a cover portion and a depending flange portion, a part of said flange portion being shaped to provide a circumferential apron horizontally disposed, consisting of an oblique top portion and a double folded horizontal flat lower portion, said lower portion formed by bending the margin of said apron inwardly beneath said oblique portion, and again bending the margin so as to be disposed under said inwardly bent portion, thereby forming a double folded annular flat surface, and holding means formed in said flat surface for attachment of said closure to a receptacle.
8. A closure for a receptacle comprising a cover portion and a depending flange portion shaped adjacent its lower extremity to provide a circumferential apron, said apron comprising an oblique laterally extending portion folded inwardly at its outer edge to form a horizontal portion, and again folded back on itself, forming a two-ply flooring for said apron, and interrupted screw threads formed from said apron for engagement of said closure with a receptacle.
- Signed at Toledo, in the county of Lucas and State of Ohio, this 30th day of June, 1923.

LESLIE R. N. CARVALHO.
